US00D615869S

(12) **United States Design Patent**
Toh et al.

(10) **Patent No.:** **US D615,869 S**
(45) **Date of Patent:** **** May 18, 2010**

(54) **CONTAINER**(75) Inventors: **Kiat Cheong Toh**, Forest Hills, NY (US); **Liam Hawry**, Chicago, IL (US)(73) Assignee: **Colgate-Palmolive Company**, New York, NY (US)(**) Term: **14 Years**(21) Appl. No.: **29/338,295**(22) Filed: **Jun. 9, 2009**(51) **LOC (9) Cl.** ..... **09-01**(52) **U.S. Cl.** ..... **D9/529**; D9/542; D9/552; D9/558; D9/449(58) **Field of Classification Search** D9/500, D9/516, 521–522, 529–530, 537–543, 544–547, D9/549, 551, 552, 558–561, 564–567, 569–575, D9/682–694, 449; 215/382–384

See application file for complete search history.

FOREIGN PATENT DOCUMENTS

EP ECD000051883-0015 7/2003

(Continued)

Primary Examiner—Carol Rademaker(74) *Attorney, Agent, or Firm*—Amy M. Fernandez(57) **CLAIM**

The ornamental design for a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawing views are included for the purpose of showing environmental structure that forms no part of the claimed design.

1 Claim, 6 Drawing Sheets# US D615,869 S
